UNITED STATES PATENT OFFICE.

CHRISTOPH GROTERJAN, OF BERLIN, GERMANY.

BOTTLE-WASHING APPARATUS.

SPECIFICATION forming part of Letters Patent No. 639,378, dated December 19, 1899.

Application filed June 7, 1898. Serial No. 682,821. (No model.)

To all whom it may concern:

Be it known that I, CHRISTOPH GROTERJAN, of Berlin, Germany, have invented certain new and useful Improvements in Bottle-Washing Apparatus; and I declare the following to be a full, clear, and exact description of the invention, such as will enable others skilled in the art to which it appertains to make and use the same.

10 My invention relates to an apparatus for cleansing bottles having a considerably-increased output and effecting a very considerable saving in working expenses as against the bottle-washing apparatus hitherto employed. In addition to the practical general arrangement of the apparatus this is mainly attained by the brushes employed as the means for cleaning the interior of the bottles, being adapted to utilize directly the propulsive power of steam issuing from a nozzle and the same steam being directly utilized for warming the washing-water.

An apparatus for bottle-washing arranged according to this invention is shown in the accompanying drawings, in which—

Figure 1 is a vertical longitudinal section of the whole apparatus; Fig. 2, a plan view of same; and Figs. 3 and 4, vertical and horizontal sections, respectively, of the motor operated directly by steam, with the axle of which motor two brushes are directly connected.

The apparatus consists of the dipping-tank *a*, which is filled with water up to a certain height and in which the bottles are first placed for a certain time in order that the impurities adhering thereto may be softened and also partially removed. On the upper edge of the longitudinal walls of this tank bars or rails *a'* are fixed, and on these a drip or drain frame *b*, mounted on four wheels *b'*, is movably arranged. The bottles, with their necks downward, are inserted in the holes of this frame, and after the bottles have been drained the draining-frame *b*, together with the bottles, is pushed to the right-hand end of the rails *a'*. The bottles then come into a comparatively shallow tank or vessel *c*, arranged at this end, where they are again partially filled with water. Above the tank *c* a brushing apparatus *d* is mounted in a bracket-like support or carrier *c'*. This brushing apparatus consists of a wheel *f*, revolvably mounted

in a casing *e*, the rim *g* of said wheel being made comparatively heavy in order that the wheel may have a considerable momentum. 55 The wheel has a groove *h* running all around it, which is provided with vanes by means of radial bars *i*. A brush *l* is connected with each end of the axle of the wheel *f*, which axle projects through the casing *e* at each end, the connection being effected by means of a socket *k*. A nozzle *m* opens into the casing *e*, which nozzle is connected with any suitable steam-supply—such, for instance, as a steam-boiler or a steam-supply pipe. The nozzle is so 65 arranged that the steam emerges therefrom with the expansive force of the vane *i*, situated immediately below it. By the force of the steam the wheel *f* and also the two brushes *l* are set in rotation, which, owing to the circumstance that each successive vane *i* receives an impulse, very soon produces an extremely-rapid revolution of the wheel *f* with the brushes *l*. The steam flowing into each separate compartment of the rim of the wheel 70 is on the rotation of the wheel of course carried with it. The lower part of the casing *e* is widened out or expanded in such a way that a free space *n* results, in which the steam carried along in the compartments of the 75 wheel-rim is ejected by centrifugal force. A pipe *o* runs downward from this space *n*, and the lower end of said pipe dips in the water of the tank *c*. A second pipe *p*, also running from the space *n*, opens into the water of the 80 tank *a*. As the tanks *a* and *c* at first and also later on (on the renewal of the water) are always again filled with cold water a powerful condensation of course takes place of the steam passing from the chamber *n* into the 85 pipes *o* and *p*, and in consequence of this condensation there very soon takes place in the water contained in the said two tanks such a heating as is necessary for the rapid softening and washing out of the impurities contained in and on the bottles. A workman stands at each side of the tank *c* and removes the bottles from the tank and places them over the rapidly-rotating brushes *l*, arranged at each side, so that the interior of the bottles is thoroughly cleansed. The workman places the brushed-out bottles, which still contain some water, into a second drip-frame 90 *q* adjoining him, from which the bottles may

be removed again by another workman and finally washed in a third tank *r*, containing pure water.

The steam consumption of the brush-motor 5 is a very small one, and steam having a pressure of one to one and one-half atmospheres suffices.

By using the double brushing apparatus hereinbefore described about two thousand 10 bottles may be cleansed per hour. For this four workmen are employed at each side of the washing apparatus, so that in all eight workmen are necessary.

I claim as my invention—

15 Apparatus for washing bottles having washing-tanks, a vaned motor-wheel, brushes se-

cured to the shaft of the wheel, a casing surrounding the motor-wheel, having a widened chamber part, a steam-inlet pipe to admit steam to the motor-wheel and pipes connected 20 to the widened chamber part of the casing to deliver the steam to the washing-tanks thereby heating the water and revolving the brushes from the same steam-supply, as set forth.

In testimony whereof I have signed my name to this specification in the presence of two subscribing witnesses.

CHRISTOPH GROTERJAN.
